UNITED STATES PATENT OFFICE

MYLES MORGAN, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS

HANDLING OF COILS OF WIRE OR THE LIKE

Application filed October 9, 1928. Serial No. 311,392.

The present invention relates to the handling of coils or bundles of wire, or like objects such as tires, hoops, etc. The invention resides particularly in an improved means 5 and method of transferring a succession of such ring-shaped bundles or articles, as moved flatwise on a conveyor or the like, to a series of suspension hooks whereon the individual bundles are impaled, for transportation to any desired point.

Heretofore, this transition from a condition of flatwise support to a condition of suspension or hanging support has involved considerable labor and attention from several operators, in the operations of lifting the bundles and impaling them on the hooks and in the manipulation of the hooks to receive the bundles,—all attended, particularly in the case of coiled wire or rods, with 20 more or less disturbance and distortion of the several convolutions of the coil structure. By my invention, the necessity for manual attention to the coils or bundles at the point of their transfer to the hooks is entirely eliminated; a single operator, stationed at a post 25 remote from the transfer point, is enabled, by the invention, to effect the transfer to the hooks of the coils or bundles from a plurality of flat conveyors,—all by the simple 30 manipulation of conveniently disposed operating levers under his control, and the transfers occurring with a minimum disturbance of the coil structures. Other and further objects and advantages of the invention will be 35 apparent from the following detailed description thereof, reference being had in this connection to the accompanying drawings, wherein—

Fig. 1 is a view in side elevation, showing 40 my invention as applied to the transfer of coils from a flat conveyor to a hook carrier.

Figs. 2 and 3 are fragmentary detail views 45 showing the transferring devices in certain positions that they assume in their cycle of operations.

Like reference characters refer to like parts in the different figures.

Referring first to Fig. 1, I have illustrated conventionally therein the outer end 50 of a conveyor of the type adapted for

the flatwise transportation of a succession of wire coils or bundles a , a , the latter, as formed on the usual reeling devices, not shown, being drawn along the floor 1 of the conveyor, between its walls 2, 2, by a series of moving dogs 3, 3 that project upwardly through the floor 1 to engage the inner peripheries of the coils a , a . As here shown, said dogs 3, 3 are carried by an endless chain or belt 4, which runs beneath the floor 1, said chain 4, near the outer end of the conveyor passing over a sprocket wheel 5 and thereafter taking a more or less sharp downward inclination, in conformity with the slope of the floor section 1' at the extreme outer end 55 of the conveyor. At said extreme outer end, the chain 4 passes around the sprocket wheel 6 from which its lower course returns in the usual manner, to the other end of the conveyor adjacent the reeling devices whereon the coils a , a are formed. When a coil or bundle a has been carried over the peak of the conveyor and onto the downwardly sloping floor section 1', its tendency is to slide 60 forward by gravity, so that the rear portion of its inner periphery engages the moving dog 3, whereby, upon discharge from the conveyor into the position indicated at a' in Fig. 1, the dog 3 in passing around the sprocket 6 is carried clear of the coil or 65 bundle so deposited in the position a' . The above described conveyor mechanism and operation, of and by itself, forms no part of the present invention, being old and well known in the art.

As shown in Fig. 1, the support for the coil or bundle in its rearwardly inclined position a' , is afforded by a seat or cradle, which consists essentially of two elements or members, namely a bottom rest 7, at a slight inclination from the horizontal, against which seats a portion of the outer periphery of the bundle, and a back rest 8, at a slight inclination from the vertical, against which rests that surface of the bundle which formerly 80 made contact with the floor of the conveyor. The two members or elements 7 and 8, which constitute the seat or cradle, stand normally in bundle-receiving position, substantially 85 at right angles to each other, thereby to form, 90 95 100

in effect, a notch wherein the bundle is deposited. Said seat or cradle 7, 8 is supported for swinging movement on a trunnion 9 provided by a stationary base 10, the connection to said trunnion being made by a suitable downward extension 11 of the back rest 8. The trunnioned seat or cradle is positioned and maintained in its bundle-receiving position of Fig. 1 by the engagement of its back rest portion 8 with a fixed stop surface 12 provided by the framework at the outer end of the flat conveyor. Said trunnioned seat or cradle is operable in the manner hereinafter described to transfer each bundle deposited therein to one of a series of hooks 13; said hooks, of which one only is shown, depend from a hook carrier 14 that runs on a suitable track 15 extending transversely of the direction of movement of the bundles on the conveyor, or row of conveyors, as the case may be.

As shown in Fig. 1, provision is made for swinging the seat or cradle 7, 8 outwardly, about its trunnion 9, to carry the coil or bundle a' toward a hook 13, whenever the operator, stationed in a pulpit 16, observes that such a hook on the carrier 14 has travelled into a position where it is opposite the bundle a' . To this end, a lever arm 17 extending from the lower end of the seat or cradle, beyond the trunnion 9, is connected by a link 18 to one arm of a bell crank lever 19 pivoted at a fixed point 20. The other arm of said bell crank lever 19 has a link connection 21 to an operating lever 22 in the pulpit 16, and it will be seen that when the lever 22 is rocked counterclockwise, the connecting links and levers will cause the seat or cradle 7, 8 to swing outwardly from the conveyor toward the hook 13, as illustrated in Fig. 2.

Such movement, taking the bundle or coil from the position a' to the position a'' , requires the cradle to travel through a considerable arc,—and a return movement through the same arc being necessary, it will be seen that the coil or bundle, as thus incompletely transferred to the hook 13, stands directly in the return path of the bottom rest portion 7 of said cradle, if the latter is allowed to maintain its normal right-angled relation to the back rest portion 8. However, according to the invention, said bottom rest portion 7 is made automatically collapsible upon the impalement of the coil or bundle on hook 13, so that as soon as position a'' is reached, the support of the coil or bundle by the cradle is completely withdrawn, allowing said coil or bundle to drop by gravity into the position a''' , Fig. 3. This takes place as the result of a special construction of the seat or cradle, as follows:—

The bottom rest portion 7, instead of being rigid with the back rest portion 8, has a pivotal connection thereto at the point 23. Therefore, in order to maintain the normal

substantially right-angled relation between bottom rest and back rest, the former must be supported at its free or outer end. Such support, as here shown, takes the form of a toggle lever, consisting of the parts 24 and 25, the part 24 being pivotally connected at 26 to the bottom rest 7, and the part 25 being journaled on the trunnion 9. Said parts 24 and 25 are connected pivotally at their opposing ends by a pin 27, and one of said parts (the part 25) has a portion 28 overlapping the edge of the other part, to prevent the collapse of the toggle, except as the part 24 may fold counterclockwise toward the part 25. In the normal coil-receiving position of the cradle, the toggle 24, 25 is in its extended position (Fig. 1) and is prevented from breaking or collapsing by the fact that the thrust from bottom rest 7 holds the parts slightly beyond dead center, in the direction away from portion 28. When the lever 22 is operated to carry the cradle into the position shown in Fig. 2, part 25 of the toggle, at the very end of this movement, is thrust forcibly against a stop 29 on base 10, thereby thrusting the pivot point 27 through the dead center position and allowing the toggle to collapse completely under the weight of the bottom rest 7 and the coil or bundle carried thereon, as shown in Fig. 3. By thus automatically collapsing the bottom rest 7 of the cradle, the coil or bundle is left free to drop by gravity onto the hook, and the return movement of the cradle to coil-receiving position takes place in the absence of any contact with, or disarrangement of, the suspended coil by the collapsed bottom rest 7. Said return movement, as here shown, is effected by the action of a spring 30, operating through a rod 31 on the lever arm 17; said spring, normally occupying the extended position shown in Fig. 1, is compressed, as shown in Fig. 2, when the operating lever 22 is thrust counterclockwise to swing the cradle 7, 8, and when said operating lever 22 is released, the compressed spring 30 becomes effective to return the parts to normal position. On this return movement, the toggle part 25 bears against a spring-cushioned stop 32 carried by the base 10 and thus, as the cradle swings clockwise, the toggle part 24 is gradually swung into alignment with the toggle part 25 until the bottom rest 7 reaches the normal position shown in Fig. 1.

I claim:

1. Apparatus for the transfer of coils or other annuli from a conveyor to a hook carrier, comprising a movable member for the support of each coil by its bottom edge in substantially vertical position, and means responsive to the movement of said member in the act of hooking said coil over one of the hooks of said carrier, for collapsing said member's support of said coil, thereby to leave said coil suspended from said hook.

2. In apparatus of the class described, the combination with a movable coil-receiving member adapted for the support of each successive coil by its lowermost edge, of a conveyor providing coil-suspending projections, means for moving said member to hook a coil over one of said projections, and means responsive to said movement for collapsing said member, thereby to leave the coil suspended from the projection. 70
3. In apparatus of the class described, means for transferring successive coils or annuli from a flat conveyor to a hook carrier, said means comprising a carriage whereon each coil or annulus deposited by said conveyor is supported on edge in a substantially vertical position, means for moving said carriage from its coil-receiving position toward said carrier into a coil-discharging position, and means operable on the arrival of said carriage at said last-named position to withdraw the edgewise support afforded said coil. 75
4. The combination with means providing hooks for the suspension therefrom of successively delivered coils or other annuli, of a cradle, whereon successive coils from a flat conveyor are deposited, said cradle providing a bottom rest for the lower edge of each coil to support the latter in a substantially vertical position, and means for collapsing said bottom rest upon that movement of said cradle which hangs a coil so supported over one of said hooks, thereby to permit the return of said cradle to coil-receiving position without disturbance of the coil so transferred to a hook. 80
5. The combination with a conveyor for the flatwise support and movement of a succession of coils or other annuli, of a mechanism for transferring the support of each coil to a suspension hook, said mechanism comprising a movable member adapted in coil-receiving position to support each coil by its lowermost edge in a substantially vertical position, and means responsive to that movement of said member which carries said coil toward a hook for withdrawing said edgewise support, thereby allowing the coil to drop, unimpeded, upon said hook. 85
6. The combination with a conveyor for the flatwise support and movement of a succession of coils or other annuli, of a mechanism for transferring the support of each coil to a suspension hook, said mechanism comprising a movable member adapted in coil-receiving position to support each coil by its lowermost edge in a substantially vertical position, means responsive to that movement of said member which carries said coil toward a hook for withdrawing said edgewise support, thereby allowing the coil to drop, unimpeded, upon said hook, and means responsive to the return movement of said member to coil-receiving position for restoring said edgewise support. 90
7. In apparatus of the class described, for the transfer of successive coils from a flat conveyor to a hook carrier, comprising a transfer member providing, in coil-receiving position, a bottom rest for the edgewise support of the coil, a toggle joint for the support of said bottom rest in its operative position and means for collapsing said toggle joint on the movement of said transfer member to coil-discharging position, thereby to free the coil as it is carried onto one of the hooks of said hook carrier. 95
8. In apparatus of the class described, for the transfer of successive coils from a flat conveyor to a hook carrier, comprising a transfer member providing, in coil-receiving position, a bottom rest for the edgewise support of the coil, a toggle joint for the support of said bottom rest in its operative position, means for collapsing said toggle joint on the movement of said transfer member to coil-discharging position and means for restoring said toggle joint to distended position on the return of said transfer member to coil-receiving position. 100
9. Apparatus for transferring coiled material from a flat conveyor to a hook carrier, comprising a cradle to receive successive coils from said conveyor, said cradle providing a bottom rest for the edge of said coil, a toggle joint normally holding said bottom support in operative position, and means responsive to relative approaching movement between said cradle and said hook carrier, in the act of impaling a coil in said cradle upon a hook of said carrier, for collapsing said toggle joint, thereby freeing said coil of its edgewise support by said bottom rest, and transferring its support to said hook. 105
